DESIGN FOR A TOOL FOR REMOVING CORN FROM THE COB

Dale Parsons, Verdon, Nebr.

Application April 22, 1940, Serial No. 91,867

Term of patent 14 years

To all whom it may concern:

Be it known that I, Dale Parsons, a citizen of the United States, residing at Verdon, in the county of Richardson and State of Nebraska, have invented a new, original, and ornamental Design for a Tool for Removing Corn from the Cob, of which the following is a specification, reference being had to the accompanying drawing, forming a part thereof.

Fig. 1 is a plan view of a tool for removing corn from the cob showing my new design.

Fig. 2 is a side elevational view thereof; and Fig. 3 is an end elevational view thereof.

I claim:

The ornamental design for a tool for removing corn from the cob, as shown.

DALE PARSONS.
